UNITED STATES PATENT OFFICE

172,499

THERMOSTAT CASING OR SIMILAR ARTICLE

Harry R. Greene, Pasadena, Calif., assignor to
Affiliated Gas Equipment, Inc., Cleveland, Ohio,
a corporation of Delaware

Application November 9, 1953, Serial No. 27,501

Term of patent 14 years

(Cl. D52—7)

To all whom it may concern:

Be it known that I, Harry R. Greene, a citizen of the United States, residing in Pasadena, county of Los Angeles, State of California, have invented a new, original, and ornamental Design for a Thermostat Casing or Similar Article, of which the following is a specification, reference being had to the accompanying drawing, forming part thereof.

Figure 1 is a front perspective view of a thermostat casing, showing my new design;

Figure 2 is a front elevation thereof;

Figure 3 is a top plan view;
Figure 4 is a right side elevation; and
Figure 5 is a left side elevation.

I claim:

The ornamental design for a thermostat casing or similar article, substantially as shown.
